UNITED STATES PATENT OFFICE.

LOUIS R. MUSKAT, OF CHICAGO, ILLINOIS, ASSIGNOR TO TRIANGLE PACKAGING COMPANY, OF CHICAGO, ILLINOIS, A CORPORATION OF ILLINOIS.

GLUE-APPLYING APPARATUS.

Application filed October 31, 1927. Serial No. 229,822.

This invention relates to improvements in glue applying apparatus and it consists of the matters hereinafter described and more particularly pointer out in the appended claims.

The primary object of the invention is to provide an apparatus of the kind described, especially adapted for use in carton factories and like establishments for applying glue to certain end flaps of paper cartons before folding them over into superposed relation.

Another object of the invention is to provide a portable, power driven apparatus of this kind, which is fast and positive in operation and which can be easily adjusted to regulate the amount of glue applied to the work operated upon.

These objects of the invention as well as others, together with the many advantages thereof will more fully appear as I proceed with my specification.

In the drawings:

Fig. 1 is a view in front elevation of an apparatus of this kind, embodying therein the preferred form of my invention.

Fig. 2 is a vertical sectional view on an enlarged scale through the top end of the apparatus as taken on the line 2—2 of Fig. 1.

Figs. 3 and 4 are further vertical sectional views through said Fig. 2 as taken on the lines 3—3 and 4—4 respectively, thereon.

Fig. 5 is a perspective view of a certain saddle block or casting forming a part of my improved apparatus.

Referring now in detail to that embodiment of the invention illustrated in the accompanying drawing, 1 indicates as a whole the standard of my improved apparatus which embodies an upright post 2 secured at its bottom end to a crow foot like base 3 having casters 4 by which the apparatus is rendered easily portable. Secured to the top end of the post is a bracket casting 5 having a horizontal, forwardly and rearwardly extending bushed bearing opening 6 and a longitudinally extending, vertically depending flange 7 arranged to the front of the post. To the front face of this flange is fixed a rectangular open top box like container 8 for the glue or other adhesive employed. On the top end said bracket casting which is flat as indicated at 9 in Fig. 4 is a pair of upright, laterally spaced ears 10—10.

Journalled in the bearing opening 6 is

a shaft 11 and on the front end thereof is fixed a roll 12 of such a diameter as to bring its bottom peripheral portion well into the glue or adhesive in the container 8.

On the rear end of this shaft is secured a pulley 13 and between this pulley and the bracket 5, is secured a spur gear 14. 15 indicates a saddle block (shown in perspective in Fig. 5) arranged above the flat part 9 of the bracket casting 5 between the ears 10—10 thereof. Said block includes a flat base 16, upwardly and laterally inclined end arms 17—17 and an apertured boss 18 arranged between and parallel with said arms. Extending through the ears 10—10 of the bracket casting is a shaft 19 which also extends through the saddle block boss 18 whereby said block is capable of being tilted in the plane of the shaft 11 within certain limitations. In the base of said block to the front and rear of the boss 18 are provided adjusting screws 20—20 by which said block may be tilted and then locked in the desired position. In the arms 17 of said block is fixed a pin 21 parallel with but offset to one side of the shaft 11 and on said pin is mounted a swingable arm or plate 22 with its free end overhanging the flat part 9 of the bracket casting 5.

In the free end of said arm or plate is journalled a shaft 23 arranged above and parallel with the shaft 11 and on the front end of the shaft 23 is fixed a roll 24 having a peripheral engagement with but being of a diameter smaller than that of the roll 12 so that glue or adhesive is transferred from one roll to the other. On the rear end of the shaft 23 is secured a spur pinion 25 which meshes with the gear 14, said pinion and gear being of such proportions that the peripheral speeds of said rolls are the same. Interposed between the arm or plate 22 and one of the arms of the saddle block is a spring 26 which normally holds the rolls in peripheral engagement. By manipulating the screws 20—20 the rolls may be so arranged that either a full face peripheral engagement may be had between said rolls or an engagement between the desired end portions may be had and in this manner the amount of glue or adhesive transferred from one to the other may be carefully determined, the gear and pinion 14 and 25 having teeth of such radial length and so formed

as to permit of this adjustment without disturbing the desired meshing engagement. If desired a guard 27 may be carried by the plate or arm 22 to enclose portions of said 5 gear and pinion.

On the top of the container 8 to one side of the roll 12 is mounted a plate 28 to determine the amount of glue or adhesive picked up by said roll. This plate is mounted in 10 suitable guides on the top of the container and may be adjusted toward or away from said roll by a hand screw 29 and locked in the desired position by thumb nuts 30 which take through said plate and extend into the 15 guides therefor.

31 indicates a plate fixed to and rising from the front wall of the container 8 as best shown in Fig. 1. This plate has a bevelled top edge 32 at one end by which the material to which the glue or adhesive is to be applied, may be guided between the front ends of the rolls 12 and 24. At the other end of said plate is a rod like extension 33 against which said material may be folded 25 into the desired position as when said material happens to be the flaps at the ends of cartons and the like.

Mounted on the post 2 just above the crow foot base is a U shaped bracket 34 including 30 top and bottom arms 35—35 and a horizontally disposed laterally arranged motor supporting plate 36. Said arms are split at their ends so that they may be clamped to the post and on said plate is a motor 37. On 35 the bottom arm is fixed a rearwardly extending stud 38 on which is journalled a combined large and small pulley 39 and 40 respectively. The large pulley is driven from the motor by a belt 41 while the pulley 13 on 40 the roll shaft 11 is driven from the small pulley 40 by a belt 42.

In operation the material to which glue is to be applied, is placed upon the inclined edge of the guide plate 31 and is passed or 45 guided between the roll 12 and 24, the glue on said roll being offset therefrom upon said material. As this material passes between the rolls, the top one will rise that distance corresponding to the thickness of said material by swinging about the arm or plate 22, the spring 26 returning the parts to normal position after passage of the material between said rolls. Should it be desired to have more glue at the front end of the rolls 50 than at the rear end, the screws 20—20 on the saddle block 15 are manipulated to produce a slight upward tilt to the front end of the roll 24 to space it from the roll 12 a short distance at that end. If it is desired that 55 more glue be picked up by the rear end of the roll 24, then the screws 20—20 are manipulated in the reverse manner.

The apparatus is light in weight and is so easily portable as to be readily brought to 60 the job at hand. Thus it is a handy and 65

efficient apparatus for use in all hand glueing operations employed in small shops when the larger glueing apparatus would be impractical. It is fast in operation and the parts are strong and rigid and so arranged 70 that they will not readily get out of order.

While in describing my invention, I have referred in detail to the form and arrangement of the various parts thereof, the same is to be considered as by way of illustration 75 only and not by way of limitation except as may be pointed out in the appended claims.

I claim as my invention:

1. An apparatus of the kind described embodying therein a support, an open top container arranged at the front thereof, a driving shaft journalled in said support, a roll fixed to said shaft and arranged with a part of its periphery in said container, a saddle block mounted on the support and capable of an adjustable tilting movement about an axis at a right angle to said support, an arm pivotally mounted at one end on said saddle block about an axis parallel with said driven shaft, a second shaft journalled in the other end of said arm and arranged parallel with the driven shaft, a roll on said second shaft adapted for peripheral engagement with said first roll and means operatively connecting said shafts. 80 85 90 95

2. An apparatus of the kind described embodying therein a support, an open top container arranged at the front thereof, a driving shaft journalled in said support, a roll fixed to said shaft and arranged with a part of its periphery in said container, a saddle block mounted on said support and capable of an adjustable tilting movement about an axis at a right angle to said driven shaft, adjusting screws threaded in said saddle block and engaging said support for effecting said adjustment, an arm pivotally mounted at one end in said saddle block on an axis parallel with said driven shaft, a second shaft journalled in the other end of said arm, parallel with the driven shaft, a roll on said second shaft adapted for peripheral engagement with said first roll and means for operatively connecting said shafts. 100 105 110 115

3. An apparatus of the kind described embodying therein, a support having laterally spaced ears at its top end, a driven shaft journalled in said support in a plane at a right angle to said ears, a container at the front of said support, a roll fixed to said shaft with a part of its periphery arranged in said container, a saddle block disposed on said support between said ears, means connecting said block and ears permitting a tilting adjustment of said block, an arm pivoted at one end to said block about an axis offset from but parallel with said driven shaft, a second shaft pivoted in the other end of said arm and arranged parallel with an 120 125 130 above the driven shaft, a roll on said second

shaft adapted for peripheral engagement with said first roll and means operatively connecting said shafts.

4. In an apparatus of the kind described, 5 a support, an open top container at the front of said support, a pair of rolls journalled with respect to said support and adapted for a peripheral engagement, one of said rolls having a part of its periphery disposed in 10 said container, means for operatively driv-

ing said rolls, a guide plate at the front of said container and having one edge disposed to guide material between said rolls at one end thereof and a rod like extension on said plate at the other end thereof against which 15 said material may be engaged when folding the same after passing between said rolls.

In testimony whereof, I have hereunto set my hand, this 25th day of October, 1927.

LOUIS R. MUSKAT.
